UNITED STATES PATENT OFFICE

164,887

KNIFE OR SIMILAR ARTICLE

Franz Wagner, Chicago, Ill., assignor to Ecko Products Company, Chicago, Ill., a corporation of Illinois

Application May 17, 1951, Serial No. 15,212

Term of patent 3½ years

(Cl. D22—3)

To all whom it may concern:

Be it known that I, Franz Wagner, a citizen of the United States, residing at Chicago, county of Cook, State of Illinois, have invented a new, original, and ornamental Design for a Knife or Similar Article, of which the following is a specification, reference being had to the accompanying drawing, forming part thereof.

Fig. 1 is a front elevational view of a knife or similar article, showing my new design.

Fig. 2 is a side elevation thereof.

Fig. 3 is an enlarged transverse section taken on line 3—3 of Fig. 1.

Fig. 4 is a similar section taken on line 4—4 of Fig. 1.

The essential features of my design reside in the parts shown in full lines.

I claim:

The ornamental design for a knife or similar article, as shown and described.

FRANZ WAGNER.
